UNITED STATES PATENT OFFICE.

JOSEPH L. BOISVERT, OF BOURBONNAIS, ILLINOIS.

POULTRY NEST.

Application filed January 8, 1923. Serial No. 611,520.

To all whom it may concern:

Be it known that I, JOSEPH L. BOISVERT, a citizen of the United States, residing at Bourbonnais, in the county of Kankakee and State of Illinois, have invented new and useful Improvements in Poultry Nests, of which the following is a specification.

This invention relates to poultry nests, and its object is to provide a novel and improved structure of this kind capable of being easily cleaned and sprayed to keep the same free of vermin.

10 The invention also has for its object to provide a knockdown nest structure to facilitate cleaning, and also to save space in shipment and storage.

15 The objects stated are attained by means of a combination and arrangement of parts to be hereinafter described and claimed, and 20 in order that the same may be better understood, reference is had to the accompanying drawing, in which—

Figure 1 is a front elevation of the nest;

25 Figs. 2 and 3 are sections on the lines 2—2 and 3—3, respectively, of Fig. 1;

Figs. 4, 5 and 6 are perspective views illustrating a corner structure;

Fig. 7 is an enlarged sectional detail of such corner structure at the top;

30 Fig. 8 is a similar view of the corner structure at the bottom;

Fig. 9 is a perspective view showing a fragment of one of the side walls of the nest, and Fig. 10 is a perspective view of a corner structure at the top.

35 Referring specifically to the drawing, the nest is a substantial rectangular box-like structure having sides 10, a rear wall 11, a bottom 12 and a top 13, these parts being all 40 made of sheet metal. The bottom is slightly sunk toward the center. The top has a downward bend 14 in front terminating a considerable distance short of the bottom to leave a front opening or entrance to the nest.

45 To the bottom, at the front or entrance, is secured an upstanding guard strip 15 rising to a suitable height for preventing the eggs and straw or other nest material from being crowded out of the nest through the entrance, the strip extending throughout the entire width of the entrance. The front edges of the sides 10 are outwardly rolled, as shown at 16, and the front edge of the bottom 12 has an upward roll 17, these rolls being 50 for the purpose of obtaining a smooth entrance.

The rear wall 11 has forwardly directed top, bottom and side flanges 18, 19, and 20, these being formed integral with said wall and having their adjacent or meeting ends overlapped and soldered together. The side walls 10 also have inturned rear, top and bottom marginal flanges 21, 22 and 23. The side walls 10 are positioned inside the flanges of the rear wall, and they are held in place at the bottom by upstanding screws or rivet studs 24 carried by the bottom flanges 19 of the rear wall 11 and entering apertures 25 in the bottom flanges 23 of the side walls 10. At the top, the side walls are held in place 60 by pins 26 passing through alined apertures in the top 13 and the lapping flanges 18 and 22. The pins 26 are removable, in view of which it will be evident that the rear and side walls 10 and 11 are detachably connected. 65

With the side walls 10 in place, the bottom 12 is inserted therebetween, to seat on the flanges 23, and it is provided with apertures to receive the studs 24, and studs 27 carried by the flanges 23. The bottom 12 is provided with upstanding marginal flanges 28 at the sides and the rear. 70

The top 13 is removably fitted to the side and rear walls 10 and 11, and it has downturned marginal flanges 29 at its sides lapping the side walls. In front, the flanges 29 are spaced from the bend 14 so that the latter may clear the side walls and seat between the rolls 16 as shown in Fig. 1. 75

By the structure hereinbefore described an all-metal nest is had, which, owing to the knock-down construction enables it to be easily kept clean and in a sanitary condition, and when in knockdown form, it takes up very little space, which is a decided advantage and convenience in shipment and storage. 80

I claim:

85 A poultry nest comprising a box-like structure having an entrance, and composed of side walls having inturned top, bottom and rear flanges, a rear wall having inturned top, bottom and side flanges, the top and bottom flanges of the side and rear walls lapping, fasteners seating removably in said lapping flanges, a bottom seating removably on the bottom flanges of the side walls and secured by the bottom ones of the aforesaid fasteners, and a removable top. 90

95 In testimony whereof I affix my signature.
JOSEPH L. BOISVERT.
